RAYMOND H. OLLEY, OF SYRACUSE, NEW YORK, ASSIGNOR TO CROUSE-HINDS COMPANY, OF SYRACUSE, NEW YORK, A CORPORATION OF NEW YORK

PORTABLE ELECTRIC LAMP

Application filed August 18, 1927. Serial No. 213,956.

This invention relates to portable electric lamps and has for its object a particularly simple and efficient and compact construction, whereby the parts are held in assembled 5 position and also means by which the body and the lamp guard are grounded and also means by which the cable enclosing the service wires is so connected to the lamp socket that the wires are relieved of mechanical tension in the ordinary use of the lamp.

The invention consists in the novel features and in the combinations and constructions hereinafter set forth and claimed.

In describing this invention, reference is 15 had to the accompanying drawings in which like characters designate corresponding parts in all the views.

Figure 1 is an elevation of this portable lamp.

20 Figure 2 is a similar elevation with the handle securing means and section of the guard removed and the handle partly broken away.

Figure 3 is a side elevation of parts seen in 25 Figure 2, with the handle displaced lengthwise of the cable.

This portable lamp comprises generally, a body, a lamp socket, a handle, means for securing the lamp socket to the body and additional means for securing the handle to the body, also a guard including a section rigid with the body and a section movably connected to the handle securing means, the body and the handle securing means enclosing the 30 lamp socket and a portion of the handle and a grounding conductor electrically connected to the body and to the ground wire of the cable which extends lengthwise through the handle, the grounding conductor also having means 35 for gripping the cable to relieve the wires of mechanical tension.

1 designates the body which is of metal, it being semi-circular in cross section and having a semi-cylindrical recess in which the 45 lamp socket 2 is located and also having a larger substantially semi-cylindrical recess 3 at its lower or outer end in which an enlarged head 4 of the handle 5 is located. The lamp socket 2 may be of any suitable form, size and 50 construction.

The means for securing the lamp socket to the body, as here shown comprises a metal strap 6 semi-circular in general outline and having outwardly turned lugs 7 at its ends which are secured, as by screws 8, in shallow 55 recesses 9 in the edge of the body 1, the strap lying in a peripheral groove 10 in the lamp socket body 2. The means for securing the handle to the body is complementary to the body and comprises a semi-cylindrical sleeve 60 11 having recesses complementary to the recesses 2^a and 3 of the body, the sleeve 11 being clamped toward the body on the handle by screws 12 extending through holes in lugs 13 on the semi-circular sleeve 11 and threading 65 into holes 14 in lugs 15 on the body.

The body 1 is formed with a guard section 16 integral therewith, this being in the form of a cage and having a stud 17 at its outer end to which is secured a hook 18 by means 70 of which the lamp may be hung on any suitable support.

19 is a guard section complementary to the section 16 but in the form of a reflector, the guard section 19 being movably connected as 75 by a hinge pin 20 to the semi-circular sleeve 11.

The guard section has a semi-circular notch 21 at its outer end for fitting around the base of the stud 17 and with a lip 22 around the notch. A fastening member as a wing nut 23 is movable lengthwise of the stud 17 and has an annular flange 24 for skirting the lip 22 and holding the guard section 19 in its normal position. By unscrewing the wing nut 85 23, the guard section 19 can be swung on its pivot to open the guard and permit the removal and replacement of the lamp 25.

26 is a cable embodying three wires 27, 28 and 29, two of which are connected to the wire 90 terminals of the socket in any suitable manner.

30 is a grounding conductor for grounding the lamp body and the guard, this being a rigid piece of metal located within the handle 95 and the semi-cylindrical sleeve 11, it being here shown as rigidly secured, as by spot welding at 31, to the strap 6 and having a terminal 32 for connection to the ground wire 29. This rigid conductor 30 is also pro- 100

vided at its outer end with a device for gripping the cable.

The cable grip here shown comprises jaws 33, 34, the former being secured as by spot 5 welding to the lower end of the conductor 30 and the latter being clamped toward the former in order to grip the cable by suitable means as screws 35 extending through lugs on said jaws 33, 34, the lugs on one of the jaws 10 being threaded. By reason of the cable grip, tension strain on the wires and on the wire terminals due to the pulling that the cable receives in the normal use of the lamp, is avoided.

15 This lamp is particularly advantageous in that it consists of a few compactly arranged parts which provide means for grounding the metallic parts of the lamp as the lamp body, guard etc.

20 What I claim is:

1. A portable electric lamp comprising a body, a lamp socket, a handle, means for securing the lamp socket to the body and additional means for securing the handle to the body, whereby the body may be removed 25 from the handle without removing the socket from the body.

2. A portable electric lamp comprising a body, a lamp socket, a handle, the body partly 30 enclosing the lamp socket and the handle, means for securing the lamp socket to the body, means for securing the handle to the body, the latter means being complementary to the body and enclosing the lamp socket and 35 the handle and covering the lamp socket securing means, and means for clamping the handle securing means to the body.

3. A portable electric lamp comprising a body, a lamp socket, a handle, the body partly 40 enclosing the lamp socket and the handle, means for securing the lamp socket to the body, means for securing the handle to the body, the latter means being complementary to the body and enclosing the lamp socket and 45 the handle and covering the lamp socket securing means, means for clamping the handle securing means to the body and a lamp guard including a portion rigid with the body and a portion carried by the handle securing 50 means.

4. A portable electric lamp comprising a body, a lamp socket, a handle, means for securing the lamp socket to the body and additional means for securing the handle to the body, the body and the handle securing means 55 being complementary to each other and enclosing the lamp socket and a portion of the handle, the lamp socket securing means comprising a strap secured at its ends to the body with its intermediate portion encircling the lamp socket.

5. A portable electric lamp comprising a body, a lamp socket, a handle, a cable comprising wires connected to the lamp socket 60 terminals and a grounding wire the cable ex-

tending into the handle and a conductor for grounding the body connected to the grounding wire, said conductor being located within the body and the handle, and securing the socket to the body.

6. A portable electric lamp comprising a body, a lamp socket, a handle, a cable having wires connected to wire terminals of the lamp socket and means connecting the body and the cable to relieve the wires of tension, 70 said means being located within the body and the handle.

7. A portable electric lamp comprising a body, a lamp socket, a handle, means for securing the handle to the body, a cable extending lengthwise through the handle and embodying wires connected to the lamp socket terminals and a grounding wire, a conductor housed within the body and said securing means and electrically connected to the 80 ground wire and to the body of the lamp.

8. A portable electric lamp comprising a body, a lamp socket, a handle, means for securing the lamp socket and the handle to the body, a cable extending lengthwise through the handle and embodying wires connected to the lamp socket terminals and a grounding wire, a conductor housed within the body and said securing means and electrically connected to the ground wire and to the body of the lamp, the conductor having means for gripping the cable within the handle.

9. A portable electric lamp comprising a body, an electric lamp socket with suitable terminals, a handle, the body partly enclosing the lamp socket and the handle, a metal strap for securing the lamp socket to the body and having its ends secured to the body, a cable extending lengthwise through the handle and having wires for connection to the wire terminals of the socket and a grounding wire, a grounding conductor connected to the strap and to the ground wire and means for securing the handle to the body, said means being complementary to the body and enclosing the handle and the socket and covering said strap and contiguous portion of the grounding conductor.

10. A portable electric lamp comprising a body, an electric lamp socket with suitable terminals, a handle, the body partly enclosing the lamp socket and the handle, a metal strap for securing the lamp socket to the body and having its ends secured to the body, a cable extending lengthwise through the handle and having wires for connection to the wire terminals of the socket and a grounding wire, a grounding conductor connected to the strap and to the ground wire and means for securing the handle to the body, said means being complementary to the body and enclosing the handle and the socket and covering said strap and contiguous portion of the grounding conductor, the grounding con- 115

130

ductor also having means for gripping the cable within the handle.

11. A portable electric lamp comprising a body, a lamp socket, a handle, means for securing the lamp socket and the handle to the body, a guard including a section rigid with the body and a section carried by the means for securing the handle to the body, the section carried by the body being formed with a stud at its outer end and the section carried by the handle, securing means being movable relatively thereto and having a portion partly surrounding the stud and a member movable lengthwise of the stud and coacting with the free end of the movable guard section for securing the guard section in position.

12. In testimony whereof, I have hereunto signed my name, at Syracuse, in the county of Onondaga, and in the State of New York,

20 this 8th day of August, 1927.

RAYMOND H. OLEY.
